UNITED STATES PATENT OFFICE.

CHARLES A. ALDEN, OF STEELTON, PENNSYLVANIA, ASSIGNOR TO THE PENNSYLVANIA STEEL COMPANY, OF PHILADELPHIA, PENNSYLVANIA, A CORPORATION OF PENNSYLVANIA.

RAILROAD-CROSSING.

No. 831,759.

Specification of Letters Patent.

Patented Sept. 25, 1906.

Application filed February 3, 1906. Serial No. 299,275.

To all whom it may concern:

Be it known that I, CHARLES A. ALDEN, a citizen of the United States, residing at Steelton, in the county of Dauphin and State of Pennsylvania, have invented certain new and useful Improvements in Railroad-Crossings, of which the following is a full, clear, and exact description, reference being had to the accompanying drawings, of which—

Figure 1 is a plan view of a crossing in which one form of my invention is embodied. Fig. 2 is a section on line *x x*, Fig. 1. Fig. 3 is a section on line *y y*, Fig. 1. Fig. 4 is a plan view of a crossing embodying a modified form of the invention. Fig. 5 is a section on line *z z*, Fig. 4.

The object of this invention is to provide an improved crossing for railroads or rail-ways in which the crossing-points shall be of hard metal and which will withstand the wear and tear of heavy travel to which this class of crossings is subjected and also to provide a hard-metal bearing for the false flanges of guttered wheels in passing over the crossing-grooves.

The precise character of the invention will hereinafter appear.

In the drawings, Figs. 1, 2, and 3 show a form of crossing in which a steam-railroad track is crossed by a street-railway track or girder tram-rail. In said figures, 1 designates the railway-rails; 2, the main track or stock rails of the railroad; 3, the guard-rail, and 4 the bearing-rail. The ends of the rail-way-rails 1 abut, respectively, against the outer sides of the bearing-rail 4 and the guard-rail 3, as seen in Fig. 1. It will be seen also that the guard-rail and also the bearing-rail are bent outwardly at 3^a and 4^a, Fig. 1, and are recessed vertically to permit the insertion and retention of the sides, respectively, of a hard-metal piece 5, which hard-metal piece is provided with crossing-grooves 6 6^a, the upper surface of said wear-plate at the meeting of said grooves constituting the crossing-points, where the greatest amount of wear occurs when a wheel is passing over the crossing. The wear-plate is composed of the portion 7, inserted in the recessed inner side of the guard-rail, webs 8, and flooring portion 9 for the grooves 6 and 6^a, also the portion 10, whose upper or bearing surface is of a width extending from the

inner edge of the main or stock rails entirely across the full width of the heads of said rails 55 and is inserted into the recess in the bearing-rail, the ends of the stock or main rail abutting against the ends of the portion 10 of said hard-metal piece. These parts are all firmly secured together by means of bolts 11 passing through the respective rails and through the web portions 8 of the hard-metal piece.

The form of the invention shown in Figs. 4 and 5 does not materially differ from that of Figs. 1, 2, and 3, except that the part of the 65 portion 10 of the hard-metal piece 5 of the width of and in line with the head of the main or stock rail is extended inwardly at 10^a, as also the floor portion 9 of groove 6 and web portions 8, and abuts against corresponding extension of the adjacent crossing-piece, said extensions thus constituting the main rail between the crossing-points. In practice of course the joints between said extensions 10^a (marked 11) and between the 75 ends of the guard-rail portions, (marked 12,) as also between the bearing-rail portions, (marked 13,) are staggered or broken with relation to each other for the obvious purpose of strengthening the crossing at such points. 80

The advantage of this construction is that it gives a complete hard-metal bearing for wheels when passing over the crossing on either track, and the particular advantage of having the part 10 of the wear-plate of a 85 width to extend entirely across the main or stock rail and into the recess in the bearing-rail is that it provides a hard-metal bearing at the crossing for false flanges of "guttered" wheels passing along the main rails.

Having thus described my invention, I claim as new and desire to secure by Letters Patent—

1. In a crossing, the combination of the main rails, the guard-rails, the bent-out bearing-rails, the hard-metal wear-plates having a portion extending across the full width of the heads of the main rails and into the bent-out portion of the bearing-rails, the crossing-rails abutting against said guard-rails, and bearing-rails, respectively, together with means for securing said several parts together, substantially as set forth.

2. In a crossing, the combination of the main rails, the guard-rails bent out and recessed, the bearing-rails bent out and re-

cessed, the hard-metal wear-plates having a portion extending into the recess of the guard-rails, and having also a portion extending across the full width of the heads of 5 the main rails and into the recessed portion of the bearing-rails, the crossing-rails abutting against said guard-rails, and bearing-rails respectively, together with means for

securing said several parts together, substantially as set forth.

In testimony whereof I have hereunto affixed my signature.

CHARLES A. ALDEN.
